UNITED STATES PATENT OFFICE

CHESTER A. FRICK, OF MUNCIE, INDIANA, ASSIGNOR TO GLASCOCK BROTHERS MANUFACTURING COMPANY, OF MUNCIE, INDIANA, A CORPORATION OF INDIANA

DESIGN FOR A BOTTLE-DISPENSING CABINET

Application filed June 21, 1929. Serial No. 31,792. Term of patent 14 years.

To all whom it may concern:

Be it known that I, CHESTER A. FRICK, a citizen of the United States, residing at Muncie, in the county of Delaware and State of Indiana, have invented a new, original, and ornamental Design for Bottle-Dispensing Cabinets, of which the following is a specification.

The figure is a perspective view of a bottle dispensing cabinet showing my new design.

I claim:

The ornamental design for a bottle dispensing cabinet as shown.

In witness whereof, I, CHESTER A. FRICK, have hereunto set my hand at Muncie, Indiana, this 17th day of June, A. D. one thousand nine hundred and twenty-nine.

CHESTER A. FRICK.
